T. J. KEHOE.

LATCH FOR AUTOMOBILE HOODS.
APPLICATION FILED AUG. 8, 1917.

1,364,283.

Patented Jan. 4, 1921.

Inventor

Thomas J. Kehoe

By Chester H. Braselton

Attorney

UNITED STATES PATENT OFFICE.

THOMAS J. KEHOE, OF TOLEDO, OHIO, ASSIGNOR TO THE WILLYS-OVERLAND COMPANY, OF TOLEDO, OHIO, A CORPORATION OF OHIO.

LATCH, FOR AUTOMOBILE-HOODS.

1,364,283.

Specification of Letters Patent.

Patented Jan. 4, 1921.

Application filed August 8, 1917. Serial No. 185,118.

To all whom it may concern:

Be it known that I, THOMAS J. KEHOE, a citizen of the United States, residing at Toledo, in the county of Lucas and State of Ohio, have invented certain new and useful Improvements in Latches for Automobile-Hoods, of which I declare the following to be a full, clear, and exact description.

This invention relates to improvements in 10 latches for motor vehicle hoods.

The principal object of this invention is to provide an improved latch for motor vehicle hoods, which will be very slightly in appearance and in which the moving parts 15 will be protected from the weather so as to prevent their rusting and sticking. A further object of my invention is to provide an improved hood latch which is very simply and conveniently operated. A further 20 object of my invention is to provide a hood latch having a relatively wide range, so as to take care of slight variances occurring in the process of manufacture.

Further objects, and objects relating to 25 economies of manufacture and details of construction, will definitely appear from the detailed description to follow.

I accomplish the objects of my invention by the devices and means described in the 30 following specification. My invention is clearly defined and pointed out in the appended claims.

A structure constituting a preferred embodiment of my invention is illustrated in 35 the accompanying drawing, forming a part of this specification, in which—

Figure I is a view in side elevation showing a hood equipped with latches constructed in accordance with my invention.

40 Fig. II is a detail, sectional view, taken substantially on the line II—II of Fig. I.

Fig. III is a transverse, sectional view, taken substantially on the line III—III of Fig. II and,

45 Fig. IV is a fragmentary, detail, sectional view, taken substantially on the line IV—IV of Fig. II.

In the drawings, similar reference numerals refer to similar parts throughout the 50 several views, and the sectional views are taken looking in the direction of the little arrows at the ends of the section lines.

Considering the numbered parts of the drawings, the frame 10 carries the radiator 55 11 and the hood, comprising the upper part

12, supported in any approved manner, and the lower movable part 13 hinged to the lower edge of the upper part 12, and which may be lifted in order to permit the driver to get access to the engine. The hood 60 latches, which are designated generally by the numeral 14, are constructed in accordance with my invention.

The post 15 is provided with the base flange 16, which is secured to the frame 65 member 10 by means of the screws or rivets 17. Said post is provided with a head 18. A cylindrical casing 19 is provided with a central opening 20, in the base thereof, through which the post 15 passes, said casing being slidably and rotatably mounted upon said post. A plug 21 is screwed into the upper end of the cylindrical casing 19. A spring 22 is disposed around the post 15, 70 within the casing 19, being compressed between the head 18 on said post and the base of the casing 19. The casing is provided with an integral base flange 23, which is eccentrically disposed relative to the axis of the cylindrical casing 19, as clearly appears 75 from Fig. III of the drawing, and which is provided with a cam surface 24, on its lower face, as is shown in Fig. II. A channel section 26 is secured to the hood member 13 by means of the rivets 25, and said channel 80 section is provided with inclined ends or flanges 27, forming cam surfaces, as is shown in Fig. IV of the drawing. Casing 19 is provided with an integral, laterally 85 extending handle 28, by means of which the casing 19 may be lifted and rotated in order 90 to operate the latch.

From the description of the parts given above, the operation of my device should be very readily understood. In order to release 95 the latch, the operator grasps the handle 28 and rotates the casing 19, on the post 20. This carries the eccentric base flange 23 out of engagement with the member 26, which is carried by the hood, and serves to release the 100 hood so that it may be lifted. To fasten the hood in place, the casing 19 is lifted by the handle 28, against the tension of the spring 22, until the base flange 23 is in a plane above the upper surfaces of one or the other of the 105 flanges of the channel 26 upon either of which the extension 23 may be seated depending upon the strength of the spring within the casing. The casing then can be rotated by the handle 28, so as to bring the 110

- cam surface 24 on the lower edge of the base flange 23 into engagement with the inclined portions 27 of the channel 26. The rotation of the casing by means of the handle causes the cam surfaces 24 of the base flange to ride on the inclined surface 27, of the channel 26, until the flange is completely in engagement with the upper edge of the channel 26, as shown in Fig. IV. The spring member 22 exerts a yielding pressure downward upon the casing so as to hold it yieldingly and firmly in engagement with the channel 26 carried by the hood 13, which is securely held in place.
- It will be seen that the head 18 on the post 15 furnishes a bearing for the casing 19, so that the casing is held against lateral movement. All of the working parts are enclosed within the casing, and the casing presents a very slight appearance and the parts are protected from water and moisture, so that they will not rust and become inoperative due to their sticking. The device can be operated in a very simple and convenient manner, and will hold the hood in place with a yielding pressure, and the latch has a sufficiently wide range so as to take care of variabilities in manufacture due to the different positioning of the member 26 on the hood 13, the latch being equally effective, no matter what the position of the member 26, within a reasonable range. Either one of the projecting flanges of channel 26 may be engaged by the base flange 23.
- I am aware that the particular embodiment of my invention, which I have here shown and described, is susceptible of considerable variation without departing from the spirit of my invention. I have found, however, that this particular embodiment is desirable from many standpoints, and, therefore, I desire to claim my invention specifically as well as broadly as indicated by the appended claims.
- Having thus described my invention, what I claim as new and desire to secure by Letters Patent is:
1. A device of the class described comprising the combination of a post adapted to be carried by a relatively fixed part, and provided with a head; a cylindrical casing slidably and rotatably mounted on said post, and provided with an integral laterally extend-

ing handle, and an eccentrically disposed integral base flange, with a lower cam surface; a spring disposed within said casing between the base thereof and the head of said post; and a member adapted to be carried by a relatively movable part, and provided with an upper cam surface, adapted to be engaged by the lower cam surface of said flange.

2. A device of the class described comprising the combination of a post adapted to be carried by a relatively fixed part and provided with a head; a cylindrical casing slidably and rotatably mounted on said post, and having a bearing on the head thereof, said casing being provided with an eccentrically disposed base flange; spring means normally forcing said casing downwardly; and a member adapted to be carried by a relatively movable part and having an inclined cam surface engageable by said base flange.

3. A device of the class described comprising the combination of a post; a casing slidably and rotatably carried by said post and having an eccentric base flange; spring means normally forcing said casing downwardly; and a member having an inclined cam surface adapted to coöperate with said base flange.

4. A device of the class described comprising the combination of a fixed vertical post; a casing slidably and rotatably carried by said post and having an eccentric base flange; spring means normally forcing said casing downwardly; and a member having a plurality of parallel inclined cam surfaces each of which is engageable with said base flange.

5. A device of the class described comprising the combination of a post adapted to be carried by a relatively fixed part; a casing having an integral base flange slidably and rotatably mounted on said post; resilient means for normally forcing said casing and flange downwardly; and a member adapted to be carried by a relatively movable part, and adapted to coöperate with said base flange to vary the tension of said resilient means when said base flange is rotated in contact with said member.

In testimony whereof I affix my signature.

THOMAS J. KEHOE.
